UNITED STATES PATENT OFFICE.

HENRIE CLAUSS, OF FREMONT, OHIO.

DESIGN FOR A RAZOR-SACK.

SPECIFICATION forming part of Design No. 29,020, dated July 12, 1898.

Application filed May 19, 1898. Serial No. 681,167. Term of patent 14 years.

To all whom it may concern:

Be it known that I, HENRIE CLAUSS, a citizen of the United States, residing at Fremont, in the county of Sandusky and State of Ohio, have invented and produced a new and original Design for Razor-Sacks; and I do hereby declare the following to be a full, clear, and exact description of the same, reference being had to the accompanying drawing, forming a part thereof.

In the accompanying drawing the figure represents a perspective view of a razor-sack embodying my design.

The leading feature of my design consists of an elongated approximately-rectangular-shaped body portion which increases gradually and uniformly in width from its lower to its upper end, the upper end of the body portion being formed with an approximately-rounded flap which folds on a line at right angles to the body portion of the sack.

A in the drawing represents the body portion of the sack, which is closed at its bottom end, as at 'a', and open at its upper end, as at 'a'', and formed with a cut-away portion at said upper end. The body portion increases gradually and uniformly in width from its lower to its upper end. The said body portion at its upper end is provided with an approximately-rounded flap 'a''.

30

Having now described my invention, what I claim as new, and desire to secure by Letters Patent, is—

The design for a razor-sack, substantially as herein shown and described.

In testimony whereof I affix my signature in presence of two witnesses.

HENRIE CLAUSS.
